DOUBLE TAKE-UP SPRING FOR NEEDLE-BARS ON SEWING-MACHINES.

1,370,228.

Specification of Letters Patent.

Patented Mar. 1, 1921.

Application filed October 27, 1919. Serial No. 333,771.

To all whom it may concern:

Be it known that we, THOMAS E. SCULLY and HAROLD J. LYON, citizens of the United States, residing at Los Angeles, in the county of Los Angeles and State of California, have invented new and useful Improvements in Double Take-Up Springs for Needle-Bars on Sewing-Machines, of which the following is a specification.

10 This invention relates to sewing machines and more particularly to sewing machines provided with reciprocating needle and looper elements.

15 Heretofore sewing machines of the character referred to in the following specification have been provided with a reciprocating needle or needles suitably connected to a needle bar and coöperating with a reciprocating or oscillating looper whereby a 20 thread has been passed through the thread or threads brought down through the material being sewed by the needles.

25 In machines of this character difficulty has been encountered and unnecessary loss produced because of the breaking of the several threads due to the kinking of the threads from various causes, as for instance, due to the presence of an unnecessary amount of slack thread in front of the 30 needle or needles as it or they recede from their lowermost position, and also due to the unnecessary fullness of the loop formed behind the thread when the needle recedes. This superfluous length of loop tends to 35 cause the thread or threads to follow the looper and cause the breakage of the stitching as the threads become kinked or twisted by the withdrawal of the needle.

40 It is therefore one of the objects of our present invention to provide an improvement in sewing machines having the function of reducing the unnecessary looseness of the thread in front of the needle as it recedes from the goods.

45 A further object of the invention is to provide means for automatically taking up the slack of the thread and permitting the free movement of the thread as the needle moves upwardly and downwardly; and a 50 further object of the invention is to provide means for keeping the thread in the grooves of the needles or needle when such are provided with grooves or longitudinal channels above the eye.

55 Another object of the present invention is

to provide yielding means for automatically taking up unnecessary slack in the thread as the stitching proceeds and also for controlling the length of the loop being formed so as to avoid the kinking, twisting or knotting of the thread and its consequent breaking, and also which will prevent the loop from being dragged by the looper during the operation of the latter.

60 A further object of the invention is to provide a device that may be readily attached to sewing machines without requiring any material changing or altering of the construction of the latter, and to provide a device or attachment that is simple, practicable, inexpensive, durable and that will efficiently secure the desired results.

65 With the above and other objects in view as will be rendered manifest to those versed in the art the invention consists of the construction, the combination, and the details and arrangement of the parts as more particularly described in the following specification with relation to the embodiment of the invention illustrated in the accompanying 70 drawings, in which:

75 Figure 1 is a side elevation of one form of sewing machine to which the invention is shown applied.

80 Fig. 2 is a perspective view of a portion of a sewing machine showing a portion of the pressure foot and the needle bar with our improvement attached thereon, the needle being in its uppermost position, and showing the tension controlling device as under tension to take up slack in the needle thread.

85 Fig. 3 is a view of the needle bar and its needle, the latter being in its downwardly moving position.

90 Fig. 4 is a perspective view of the pressure foot and needle bar, the latter being in its lowermost position.

95 Fig. 5 is a cross section through the needle bar showing the improved take-up device thereon.

100 Fig. 6 is a side elevation of a portion of the needle bar and of the take-up device without threads.

Fig. 7 is a front view of Fig. 6.

105 Fig. 8 is a perspective view of a portion of the pressure foot mechanism and needle bar as commonly employed, the thread being shown with the slackness produced by the operation of the needle bar.

110 Fig. 9 is a diagrammatic view showing the

needle in its lowermost position with the thread tensioned to lie close in the grooves of the needle.

Fig. 10 is a diagrammatic view showing 5 the needle partly withdrawn and indicating in full lines the condition of the loop and the position of the thread under the tension of the controlling device, the looper being shown in section.

10 Fig. 11 shows a cross section through the type of needle having longitudinal slots or channels in its front and rear faces in which the threads lie.

In the form of machine illustrated, a 15 needle bar 2 is shown as provided with a suitable means 3 in its lower end to clamp a needle or needles 4. In the present case the machine is being designed to make a double row of stitches by the use simultaneously of a pair of needles 4; these needles while not necessarily so, are shown as provided in Fig. 11 with front and rear thread receiving grooves 4^a into which it is desirable that the thread be snugly drawn during 20 the operation of the machine for the purpose of preventing the thread from kinking during the operation of the machine. The needles coöperate with the looper indicated by dotted lines at 5 in Fig. 1 and shown in section in Fig. 10, the looper having a hook 25 5^a designed to pass through the loops or loop formed by the needles or needle as the case may be. Obviously the looper is so timed that it passes to the rear of the needles 4 30 closely after the beginning of the receding movement of the needles so as to enter the loops formed in the threads as the needles move upwardly.

Heretofore because of the slackness 40 formed in the thread or threads by the upward movement of the needle the threads have always had a ready tendency to kink, twist or knot because of the looseness brought about by the upward movement of 45 the needle, and this looseness results also ordinarily in the tendency of the loop into which the looper hook has passed of being drawn back with the looper as it recedes with detrimental results.

50 Therefore to the end of accomplishing the purposes above set forth we have devised a means for automatically taking up the slackness of the thread as the needle begins its upward or receding movement to prevent 55 the kinking of the thread in the front of the needle.

While our invention may be embodied in various forms a practical construction of the same is herein illustrated wherein a take-up 60 of the thread is produced efficiently and automatically during the operation of the machine. The take-up device, as shown, comprises preferably a resilient or yielding bow 7, in this case comprising a pair of spring 65 arms 8 at the outer end of which an eye 6 is

formed, the other ends of the arms 8 being shown as coiled into a bight 9 for each arm; the terminals of the spring wire, of which the device 7 is formed in this case, being suitably mounted in a mounting in the shape of a clamp 10 that can be readily attached to and removed from the needle bar 2 without requiring any alteration in the construction of the latter. The collar 10 is provided on opposite sides with ears 11 to receive the bights 9 of the spring wire of which the take-up is formed, and the rear of the clamp 10 is provided with a set screw 12 by which the collar may be suitably secured in the desired position after having been properly adjusted on the lower end of the needle bar 2.

When the device is applied the eye 6 is so disposed as to extend forwardly from the needle bar to receive the thread or threads 85 T which are passed along the frame of the machine, as shown in Fig. 1, from suitable spools S mounted on or adjacent to the machine. After the threads are passed through the bights 9 and the eye 6 of the take-up device they are also passed through the eye of the needles to be interlocked with a thread carried by the looper 5 during the operation of the machine. As the threads T coming from the spools S are drawn down by the 90 needles 4 they pass beneath suitable friction devices F in Fig. 1, and as the needles withdraw from their lowermost position a slack is consequently formed in the thread and this slack is automatically controlled by the 95 re-action of the improved take-up device above described.

The action of the take-up device is plainly shown in Figs. 2, 3 and 4, which, due to the tension of the threads in the various positions of the needles, is caused to assume different angular positions controlled by the tension of the thread and as seen in Fig. 2 when the needles are in their uppermost position the take-up eye 6 is caused to be drawn 105 down toward the needle owing to the tension of the thread between the stitch of the thread beneath the pressure foot and the friction devices F. As the needle moves 110 down the thread is automatically drawn through the friction devices F from the spools S, and as the needles move downwardly the tension device is caused to swing 115 inwardly slightly toward the needle.

In Fig. 4 the needle and needle bar are 120 shown in their lowermost position at which time the take-up device 7 is shown as in a position close to the lower end of the needle bar, and upon the upward movement of the needle bar and needle there occurs a reduction 125 in the tension of the thread as between the friction devices F and the end of the needle as the needle reduces the distance between the friction devices F and itself. It is at this time that the resilient action of 130

the take-up device serves, by the outward movement of the eye 6, to take-up this slack that is produced in the thread and to hold the threads close in the grooves or channels 5 4^a of the needles 4 as clearly shown in Figs. 9 and 11.

As the needles begin to move downwardly the take-up device eye 6 presses outwardly, as shown in Fig. 3. This outward movement not only takes up the loose thread but furthermore prevents the loop indicated at 10 L in Fig. 10 from dragging back with the looper hook.

Were the automatic take-up device not 15 used the thread and loop would assume a condition indicated in the dotted lines at L' in Fig. 10, and it is for the purpose of overcoming this slackness shown by the dotted 20 lines L' in Fig. 10 that the present take-up device is devised and utilized and will eliminate the tendency of the loop L from being drawn back with the receding looper point 5^a.

As above stated the take-up device 7 may 25 be constructed in various forms as exigency may require, but in the construction shown the device is simple and practicable and inexpensive and may be readily applied to or removed from a needle bar and is of compact 30 construction and light in weight, and as shown, the eye coil 6 forms the spring at the ends of the arms 8, so that when the device is applied the arms are contracted and the 35 bights 9 spring into the ears 11 of the collar 10. The resiliency of the bow causes it to tend to assume a position as in Figs. 5, 6 and 7, but the threads passed through the eye 6 and tensioned will change its angular 40 position as above explained with varying tension of the thread.

Various changes may be made without departing from the spirit of our invention as claimed.

We claim:

45 1. The combination with a sewing machine having a reciprocating needle bar, of a thread take-up device comprising a resilient thread engaging member adjustably mounted upon the needle bar and adapted 50 to swing in a vertical plane.

2. The combination with a sewing machine having a reciprocating needle bar, of

a take-up device comprising a resilient wire thread engaging bow removably secured to the needle bar.

55

3. The combination with a sewing machine having a reciprocating needle bar, of a take-up device comprising a resilient bow removably secured to the needle bar, said bow consisting of a single piece of wire bent 60 to form an eye with arms diverging outwardly therefrom, said arms then bent inwardly and upwardly and then outwardly and downwardly, forming resilient bights by which the bow is supported, a collar 65 adapted to be removably attached to the needle bar, and ears on the collar adapted to be engaged by the bights of the bow for supporting the latter in normally horizontal position.

70

4. The combination with a sewing machine of a take-up device comprising a yielding bow adapted to be removably attached to the head thereof, said bow comprising an eye, arms diverging from said eye, said arms 75 terminating in yielding bights by which the bow is mounted in normally horizontal position.

5. The combination with a sewing machine of a take-up device comprising an eye, 80 yielding arms diverging from said eye, said arms terminating in inwardly and upwardly extending bights for securing the device in operative position.

6. The combination with a sewing machine having a reciprocating needle bar, of a take-up device comprising a collar removably secured to the needle bar, ears on the collar, and a yielding bow having an eye in its outer end, arms extending from said eye, 90 said arms terminating in yielding bights adapted to engage said ears for supporting the bow in normally horizontal position.

85

7. The combination with a sewing machine having a reciprocating needle bar, of a take-up device comprising a collar removably secured to the needle bar, ears on the collar, and a yielding thread engaging member 95 yielding supported in normal horizontal position on said ears.

100

In testimony whereof we have signed our names to this specification.

THOMAS E. SCULLY.

HAROLD J. LYON.
